United States Patent

Des. 235,073
Patented May 6, 1975

235,073

GAME DIE OR SIMILAR ARTICLE

John C. Warren, Exeter, N.H. 03833

Filed Apr. 20, 1973, Ser. No. 352,968

Term of patent 14 years

Int. Cl. D21—01

U.S. Cl. D34—5 DT

FIG. 2

FIG. 1

FIG. 3

FIG. 4

FIG. 1 is an elevation of a game die or similar article as seen from one side showing my new design;

FIG. 2 is a plan view of the game die shown in FIG. 1 as seen from the top;

FIG. 3 is an elevation of the game die shown in FIG. 1 as seen from the right or left side of FIG. 1, both sides being identical; and

FIG. 4 is a bottom view of the game die shown in FIG. 1 as seen from the bottom side.

I claim:

The ornamental design for a game die or similar article, as shown and described.
